INVENTOR.
George L. Willson
BY
Wm J. Dolan.
His ATTORNEY.

UNITED STATES PATENT OFFICE.

GEORGE L. WILLSON, OF NEW YORK, N. Y.

PRINTER'S BLANKET.

Application filed March 9, 1921. Serial No. 450,953.

To all whom it may concern:

Be it known that I, GEORGE L. WILLSON, a citizen of the United States, residing at New York, in the county and State of New York, have invented certain new and useful Improvements in Printers' Blankets, of which the following is a specification, reference being had therein to the accompanying drawing.

10 The invention relates to printers' blankets, and has for an object to provide a device of the character referred to which shall be highly efficient and at the same time economical in construction and operation. These 15 and other objects of the invention will in part be obvious and in part more fully set forth in the following description:

The invention consists in the novel combinations, features of construction, and improvements herein shown and described.

20 In the accompanying drawing which is referred to herein and made a part hereof, is illustrated a preferred embodiment of the invention, the same serving in connection 25 with the description herein to illustrate the principles of the invention.

Of the drawing:

Fig. 1 is a side elevation of a portion of a printer's blanket constructed in accordance 30 with the invention;

Fig. 2 is an end view of an impression cylinder showing an embodiment of this invention arranged thereon, parts being broken away.

35 A printer's blanket constructed in accordance with one feature of the invention includes in combination inner and outer sheets, each of resilient material and of a thickness less than standard and adapted for imprinting 40 directly thereon, both sheets being associated to present a combined thickness equal to standard; said sheets being interchangeable in their relative positions and each affording a suitable impression surface so that 45 an inner sheet may be transposed and become the outer sheet to form the impression receiving surface of the blanket. In one embodiment of this feature of the invention, said resilient sheets are made each with 50 a fabric base and a body portion of comminuted cork having a suitable binder and secured to said base. These and other features of the invention will be more fully

set forth and described in the following specification:

55 In the operation of a printing press, it happens from various causes that a portion of the printing surface becomes damaged or loses its proper degree of resiliency and it becomes necessary to replace the impression 60 surface. In such a case, with the printer's blanket as heretofore constructed it was necessary to remove the entire blanket in order to replace the same with a new blanket having a fresh impression surface. This 65 was wasteful and caused undue delay which, especially in the case of newspaper presses, might be very inconvenient and expensive.

The prime feature therefore of the invention resides in the means provided for 70 avoiding the expense and delay incidental to changing the entire blanket. As shown, this end is accomplished by making the blanket of a number of independent resilient portions or sheets. As heretofore described, 75 these sheets in actual operation may have their relative positions changed so that if the impression surface of an outer sheet becomes damaged, an inner sheet may be removed from its position and placed outside 80 the said outer sheet, thus presenting a fresh impression surface, while at the same time permitting the damaged sheet to be used in its new position as a portion of the blanket. It will be seen that it is desirable that these 85 separate interchangeable sheets should have a uniform resiliency, and therefore preferably they are made of the same resilient material.

Referring in detail to the drawings, there 90 is illustrated in Fig. 1 a preferred embodiment of the invention. As shown, this consists of a sheet 4 arranged on the surface of the impression cylinder of a printing press and having a base 5 made of fabric material 95 and a body portion made of a suitable resilient material. This body portion is preferably made of the substance known commercially as "insole" and which consists of comminuted cork held together with a suitable binding agent, the whole adhering to the base portion. Superposed on the sheet 4 is another sheet 7 made of suitable resilient material, preferably being constructed in like manner and of the same materials 100 as the sheet 4. However constructed, it is 105

desirable, as heretofore stated, that the sheet 7 be made of a material having the same degree of resiliency as the sheet 4. It will be seen that each of said sheets is of a character adapted for imprinting directly thereon, and it is to be noted that each sheet is of a thickness less than standard and that both sheets, when associated, present a combined thickness equal to standard, in the particular embodiment shown each sheet being of a thickness approximately half of standard.

Each of said sheets 4 and 7 has at one end an extension or tail piece of fabric by means of which it is fastened at said end to one of the reels or clamps 13 within the cylinder 8, as shown in Fig. 2. The sheets are held in place on the impression cylinder 8 by a top or draw-sheet 9 which covers the impression sheets 4 and 7 and is suitably attached at 20 its opposite ends to both the reels or clamps 13 within the cylinder, as shown in said Fig. 2, one or both of the reels being revolved, as necessary, to effect the securing in place of the impression sheets by the draw sheets. It will be seen that the sheets 4 and 7 are in 25 this manner held securely in place on the impression cylinder by the draw-sheet 9. This draw-sheet in this embodiment of the invention illustrated is made of material known commercially as "artificial leather" and is impervious to oil and water and repellent to printer's ink. The draw-sheet does not interfere with the resilient sheets in acting as the impression surface of the cylinder but serves to keep the impression sheets securely in place and from being soiled by the printer's inks and other materials used.

The invention in its broader aspects is 40 not limited to the precise construction described, nor to any particular construction, by which the same has been or may be carried into effect, as changes may be made in the details of the invention, without departing from its main purposes or sacrificing its chief advantages.

I claim:

1. A printer's blanket including, in combination, inner and outer sheets, each of resilient material and of a thickness less than standard and adapted for imprinting directly thereon, both sheets being associated to present a combined thickness equal to standard; said sheets being interchangeable in their relative positions and each affording a suitable impression-surface so that an inner sheet may be transposed and become the outer sheet to form the impression receiving surface of the blanket.

60 2. A printer's blanket including, in combination, a plurality of identical sheets in superposed relation, each having its body-portion formed of the same resilient material as the other, each of a thickness less than standard, and each adapted for im-

printing directly thereon; both sheets being cooperatively associated to present a combined thickness equal to standard and being interchangeable in their relative positions so that an inner sheet may be transposed and become the outer sheet to form the impression-receiving surface of the blanket.

3. A printer's blanket including, in combination, a plurality of identical sheets in superposed relation, each sheet being adapted for imprinting directly thereon and of a thickness approximately half of standard and comprising a base of fabric-material and a body-portion adhering thereto and composed of comminuted cork, said sheets being cooperatively associated to present a combined thickness equal to standard and being interchangeable in their relative positions so that an inner sheet may be transposed and become the outer sheet and form the impression-receiving surface of the blanket.

4. A printer's blanket including, in combination, a plurality of identical sheets in superposed relation, each sheet being adapted for imprinting directly thereon and of a thickness approximately half of standard and comprising a base of fabric-material and a body-portion adhering thereto and composed of comminuted cork, said sheets being cooperatively associated to present a combined thickness equal to standard and being interchangeable in their relative positions so that an inner sheet may be transposed and become the outer sheet and form the impression-receiving surface of the blanket; and a draw-sheet impervious to oil and water arranged over the outer sheet.

5. A printer's blanket including, in combination, a plurality of identical, interchangeable sheet-components in superposed relation, each made of resilient material and of a thickness less than standard, said components being cooperatively associated to present a combined thickness equal to standards; one component constituting a resilient support for another of the components and, while functioning as such support, having its serviceability preserved and enhanced, and also affording a suitable impression-receiving surface so that one component may be interchanged with the other.

6. A printer's blanket including, as components, a plurality of impression-receiving sheets and a draw-sheet, each of the impression-receiving sheets being adapted for imprinting directly thereon and of a thickness less than standard and constituting a resilient support for the other components and, while functioning as such support, having its serviceability preserved and enhanced and comprising a base of fabric-material and a body-portion adhering thereto and including comminuted cork; said impression-

receiving sheets being cooperatively associated to present a combined thickness equal to standard and being interchangeable with each other so that when the sheet which was 5 acting as an impression-receiving component becomes worn it may be transposed and its supporting component be substituted therefor and become the impression-receiving

component, the worn sheet then becoming a supporting-component; said draw-sheet being impervious to oil and water and repellent to printer's ink and overlying the impression-receiving sheets. 10

In testimony whereof, I have affixed my signature hereto.

GEORGE L. WILLSON.

receiving sheets being cooperatively associated to present a combined thickness equal to standard and being interchangeable with each other so that when the sheet which was acting as an impression-receiving component becomes worn it may be transposed and its supporting component be substituted therefor and become the impression-receiving component, the worn sheet then becoming a supporting-component; said draw-sheet being impervious to oil and water and repellent to printer's ink and overlying the impression-receiving sheets. ¹⁰

In testimony whereof, I have affixed my signature hereto.

GEORGE L. WILLSON.

DISCLAIMER

1,545,626.—*George L. Willson, New York, N. Y. PRINTER'S BLANKET. Patent dated July 14, 1925. Disclaimer filed May 27, 1932, by the assignee, New England Fibre Blanket Company.*

Hereby enters this disclaimer to the claims numbered 1, 2 and 5 of said Letters Patent, which are in the following words, to-wit:

“1. A printer's blanket, including, in combination, inner and outer sheets, each of resilient material and of a thickness less than standard and adapted for imprinting directly thereon, both sheets being associated to present a combined thickness equal to standard; said sheets being interchangeable in their relative positions and each affording a suitable impression-surface so that an inner sheet may be transposed and become the outer sheet to form the impression-receiving surface of the blanket.

“2. A printer's blanket including, in combination, a plurality of identical sheets in superposed relation, each having its body-portion formed of the same resilient material as the other, each of a thickness less than standard, and each adapted for imprinting directly thereon; both sheets being cooperatively associated to present a combined thickness equal to standard and being interchangeable in their relative positions so that an inner sheet may be transposed and become the outer sheet to form the impression-receiving surface of the blanket.”

“5. A printer's blanket including, in combination, a plurality of identical, interchangeable sheet-components in superposed relation, each made of resilient material and of a thickness less than standard, said components being cooperatively associated to present a combined thickness equal to standard; one component constituting a resilient support for another of the components and, while functioning as such support, having its serviceability preserved and enhanced, and also affording a suitable impression-receiving surface so that one component may be interchanged with the other.”
